DESIGN FOR AN OYSTER DISH

James M. Fenton, Trenton, N. J.

Application October 30, 1942, Serial No. 108,646

Term of patent 7 years

To all whom it may concern:

Be it known that I, James M. Fenton, a citizen of the United States, residing at Trenton, in the county of Mercer and State of New Jersey, have invented a new, original, and ornamental Design for an Oyster Dish, of which the following is a specification, reference being had to the accompanying drawing, forming part thereof.

Figure 1 is a top plan view of an oyster dish, showing my new design.

Figure 2 is a side elevational view thereof.

Figure 3 is a sectional view taken on line 3—3 of Figure 1.

I claim:

The ornamental design for an oyster dish, as shown.

JAMES M. FENTON.
